UNITED STATES PATENT OFFICE.

HERMAN S. RIEDERER AND ARTHUR PAULSON, OF NEW YORK, N. Y.; SAID PAULSON
ASSIGNOR TO CHRISTIAN IVERSON, INC., OF NEW YORK, N. Y.

FILING DEVICE.

Application filed March 2, 1927. Serial No. 172,071.

Our invention relates to improvements in filing devices, and the object of our improvement is to provide a construction of such a character as to afford ease of assembly of the 5 component parts during manufacturing operations without the use of screws, bolts or rivets with the exception of the fittings for handles, name plate and lock, thereby greatly reducing labor costs without sacrificing 10 appearance or utility but in fact rather adding thereto. Other objects include a construction which readily lends itself to ease of accessibility to the contents of the device providing rigidity and compactness and fire 15 resisting properties, and the provision of an adjustable working capacity.

We attain these objects by the mechanism illustrated in the drawings in which like reference characters refer to like parts 20 throughout the various figures, and in which

Fig. 1 is a perspective view of our improved filing device with the front extension portion shown in an open position.

Fig. 2 is a horizontal section on the line 25 2—2 of Fig. 3.

Fig. 3 is a central vertical section on a transverse plane.

Fig. 4 is a detail section on the line 4—4 of Fig. 3.

Fig. 5 is an exploded view of the outside 30 members of the box.

Fig. 6 is a similar view of the inside members.

The improved filing device consists of a 35 back 2, sides 3 and 4, bottom 5, extension 8 providing a front for the device and a cover 9 hinged to the back 2. The cover is adapted to be locked to the extension 8 when they are both in closed position by means of the 40 lugs 11 which will then enter the lock 12 secured to the extension.

The back 2 and sides 3 and 4 are preferably formed from one piece of material which in this instance is metal such as steel. 45 The sides 3 and 4 are pressed inwardly along the top edges thereof to form shoulders 13 which provide a seat for the cover 9 to rest upon when in closed position, and to also provide short upstanding flanges 14, the purpose 50 of which will presently appear. The lower edges of the back and sides are turned inwardly at right angles to form a narrow flange 15 extending around these three panels

of the device, and upon this flange the bottom 5 is adapted to rest, being simply slid into place thereon and spotwelded thereto as shown in Fig. 2.

The back 2, extends upwardly to a point flush with the shoulders 13 and along its top edge is spotwelded one member of a hinge 60 16, the other member of which is similarly secured to the cover 9.

The bottom 5 is provided with four punched-out projections 17, which serve as 65 rests to suitably support and steady the box. The extension 8 is also preferably formed from one piece of material as shown in Fig. 5, which provides a front 18 and sides or wings 19. The latter are formed with an upwardly extending ear 20 respectively, the 70 object of which will be subsequently pointed out more fully. The front 18 is also shouldered at 21 similar to the shoulders 13 of the sides 3 and 4 and for a similar purpose, and also has a flange 21' similar to 75 flange 14.

Referring to Fig. 6 to what may be termed the lining of the device, for it is double walled throughout with the exception of the 80 cover which obviously could also be so constructed, the member 22 is bent to form three panels namely, back 23 and sides 24 and 25, which are flanged at 26, in the same manner as the main body of the device, and rest, in an assembled relation, upon the bottom 5. The upper edges of the sides 24 and 25 are turned over at 24' and 25' to form a slideway within which is adapted to fit the aforesaid flanges 14 of the sides 3 and 4, and the top edge of the back 23 is bent to form 85 a flange 23' to limit the extent of the air space between the back 23 of member 22 and the back 2 of the outer walls of the device.

To the bottom 5 adjacent its front edge 95 is spot-welded one member of a hinge 28 the other member of which is similarly secured to a panel 29, the latter being shouldered at 30 for this purpose and so that a flange 30' 100 will be available to engage the inside surface of the front 18 of extension 8, the weld extending through and joining these three parts together as shown in Fig. 3 at A. The panel 29 is bent over at 31 along its top edge to form a flange which is first 105 hooked over the flange 21' of member 8 be-

fore the welding operation. A second or false bottom 27 is then dropped into place. Flanges 32 and 33 serve as spacing members to limit the extent of the separation between the panel 29 and the front 18 of extension 8.

6. Stops 34 are formed by punching the metal outwardly from the sides 24 and 25 of member 22 and therefore extend into the space between the sides 3 and 24 and 4 and 25. The stops 34 are adapted to be engaged by the ears 20 on the sides of extension 8 to limit its movement in an outward direction as shown in Fig. 1 and Fig. 3.

10. 15. To the side 3 is secured an index card holder 35 and handle 36. As this operation is subsequent to the assembly following which the final finish is applied, holes 37 are provided in the side 24 and one of the side 20 wings 19 to afford access to the rivets by which the handle and card holder are secured in place after the assembly and after the application of the final finish. The panel 29 is also apertured at 37' to afford 25 access to the rivets of the lock 12.

15. It will be noted that the hinge 28 is substantially at the extreme bottom of the device and therefore the extension 8 when 30 opened will afford maximum access to the contents, the entire front swinging open instead of only a portion thereof. The construction as described is very substantial and the air space surrounding the body portion aids materially in protecting the contents 35 more effectively against damage from possible exposure to fire.

20. In order to adjustably vary the working capacity of the device, provision may be made so that its effective depth from the extension rearwardly can be shortened and in this way a device of large capacity can be manufactured without experiencing any inconvenience through the use of an index 40 common to files of this general character which might otherwise tilt too far forwardly or rearwardly when the device was only sparsely filled.

25. With this purpose in view we have shown in Fig. 1 strips 40 which are preferably 50 spotwelded across the sides 24 and 25 of the member 22. The strips 40 are shaped to form a number of loops 41 adapted to receive the angularly bent ends 42 of a rod 43. If only a few papers or other matters are 55 in the device the rod 43 may be held in position by the loops 41 relatively near the extension 8 so that when the latter is opened the action will be similar to a file of shallow depth, and as the contents increase the rod 60 can be relocated further back in the device.

65. We claim:

1. A filing device comprising a receptacle, including a cover, a back, sides, a bottom, and a front extension hinged to the 65 said bottom, said extension having guide

wings, guides for said wings formed by the insertion of a lining member to provide double walls for said receptacle, and means for limiting the extent of the outward movement of said extension comprising punchings in the sides of the receptacle adapted to engage with the said guide wings.

2. A filing device comprising a receptacle, having three outer walls formed from a single piece, and provided with a flange along the bottom edge thereof, a bottom member adapted to rest upon said flange, a lining member all in one piece adapted to be secured within the receptacle and form inner walls therefor in spaced relation to said outer walls, and a front extension hinged to said bottom member, guide wings on said extension extending into the spaces between said inner and outer walls, means for limiting the extent of the outward movement of said extension, and a cover for said receptacle.

3. A filing device comprising a body portion, including a hinged front extension, and a cover, the body portion and the extension being provided with the inner walls in spaced relation to the outer walls thereof.

4. A filing device comprising a body portion, including a hinged front extension, and a cover, the body portion and the extension being provided with inner walls in spaced relation to the outer walls thereof, and means for reducing the working space available in the device for the contents thereof.

5. A filing device comprising a body portion, including a hinged front extension and a cover, the body portion and the extension being provided with inner walls in spaced relation to the outer walls thereof, and means for reducing the working space available in the device for the contents thereof consisting of members providing a series of openings associated with the said inner walls, and a member adapted to extend across said device and engage said openings.

6. A filing device comprising a receptacle having three outer walls formed from a single piece, and provided with a flange along the bottom edge thereof, a bottom member adapted to rest upon said flange, a lining member adapted to be secured within the receptacle and form inner walls therefor in spaced relation to said outer walls, an extension hinged to said bottom member, guide wings on said extension, means for limiting the extent of the outward movement of said extension, a cover for said receptacle, and means for reducing the working space available in the device with respect to the contents thereof.

7. A filing device comprising a receptacle including a cover, a back, sides, a bottom and a front extension hinged to the said bottom, said extension having guide wings, a member fitting within the receptacle and having por-

5 tions cooperating with the sides to form guideways for the said wings, stops provided on the said portions, and means on the wings adapted to engage the stops to limit the outward movement of the said extension.

8. A filing device comprising a receptacle including a cover, a back, sides, a bottom and a front extension hinged to the said bottom, said extension having guide wings, a 10 member fitting within the receptacle and cooperating with the sides to form guideways for the said wings, said member having punched out portions extending towards the said sides and means on the wings adapted 15 to engage the said punched out portions to

limit the outward movement of the said extension.

9. A filing device comprising a receptacle including a back and side walls and a drop front, said drop front having guide wings, 20 side linings cooperating with each of said side walls to provide guideways, for the said wings, said linings being provided with punched out portions extending towards the said side walls, and means on the guide 25 wings adapted to engage the said punched out portions to limit the outward movement of the said drop front.

HERMAN S. RIEDERER.
ARTHUR PAULSON.
